his Attorney.

UNITED STATES PATENT OFFICE

2,269,198

END PROTECTOR

Howard M. Hicks, McKeesport, Pa., assignor to
 National Tube Company, a corporation of New
 Jersey

Application December 22, 1939, Serial No. 310,621

1 Claim. (Cl. 138—96)

This invention relates to end protectors, and more particularly to those which are used on the ends of tubular articles such as pipes, couplings and the like. More specifically, the invention relates to those devices which are used for completely closing the ends of tubular articles whereby the extremity of the wall and also the interior surfaces are protected from injury.

As an instance of adaptability of the device of the present invention, reference is made to unthreaded pipes which are usually scarfed on the ends for welding at the construction site, and also to interiorly threaded pipe couplings which are screwed on the ends of the pipe prior to shipment and/or storage. It is extremely important that articles of both types be maintained against injury up to the time of their usage, and numerous devices have heretofore been proposed for accomplishing this end. However, the devices of the prior art of which I am aware are usually either costly to manufacture, complex to install and remove, or fragile in service.

It is among the objects of the present invention to provide an end protector for tubular articles which is inexpensive to manufacture, extremely easy to install and remove, and one which is, at the same time, durable in service.

The invention, then, comprises the features hereinafter fully described and as particularly pointed out in the claim, the following description and the annexed drawing setting forth in detail a certain illustrative embodiment of the invention, this being indicative of but one of the number of ways in which the principles of the invention may be employed.

In said drawing:

Figure 1 is a side elevation of the apparatus of the present invention, part of which is shown in section;

Figure 2 is an end view;

Figure 3 is a sectional view on the line III—III of Figure 1; and

Figure 4 is a sectional view on the line IV—IV of Figure 1.

Referring more particularly to the drawing, the numeral 2 designates a tubular article which, in the present instance, is shown as comprising the end of a cylindrical pipe having a substantially constant wall thickness. The extremity 50 of the tubular article 2 and also the adjacent interior wall thereof may be scarfed or machined, or the interior wall may be screw-threaded for purposes of construction, whereby it is desirable to shield not only the extremity 55

of the wall, but also the interior of the article in order to prevent possible injury thereof.

According to the teachings of the present invention, there is provided a disk-like cover plate 3 which entirely covers the end of the tubular article 2 and carries on its periphery an annular flange 4 which encloses the adjacent portion of the exterior wall. Disposed within the tubular article 2, and in contact with the interior face of the disk-like cover plate 3, there is disposed the flat base portion 5 of a saddle comprising inwardly extending right-angular portions 6, the outer extremities of which are provided with rectangularly shaped grooves 8. A flexible metallic strip metal spring 9 is disposed within the tubular article 2 and is of such size and shape as to assume a concavo-convex form when its ends are in contact with the interior surface thereof, the concave portion facing the disk-like cover plate 3 and the adjacently disposed inwardly extending right-angular portions 6 of the saddle referred to hereinbefore. The width of the spring 9 is such as to enable its accommodation in the rectangularly shaped grooves 8 in the ends of the portions 6 of the saddle; and in order to maintain the spring 9 in such position the latter, the base portion 5 of the saddle and the cover plate 3, are apertured in alignment to accommodate a bolt 10 which extends therethrough and the head of which seats against the inner and therefore convex portion of the spring. The screw-threaded end of the bolt 10 extends exteriorly of the disk-like cover plate 3 and is provided with a nut 11. In order to maintain the desired shape of the spring 9 there is disposed between the inner surface of the base portion 5 of the saddle and the outer, and therefore concave, surface of the spring 9 a tubular spacer sleeve 12 through which the bolt 10 extends.

The saddle, comprising the base portion 5, inwardly extending right-angular portions 6, and rectangularly shaped grooves 8 in the outer ends of the latter, serves to guide the entry of the spring 9 into the tubular article 2; and also to equalize the pressure of the spring against the interior surface of said tubular article. The bolt 10 and the spacer sleeve 12 serve to limit the spring action as well as to properly position the spring.

From the foregoing it will be seen that the spring 9, bolt 10, spacer sleeve 12 and saddle comprising the portion 5 and inwardly extending right-angular portions 6 may be easily inserted in the end of the tubular article 2, after which the disk-like cover plate 3 and nut 11 may

be applied, and the nut 11 so adjusted as to force the spring 9 to properly grip the interior surface of the tubular article 2. The removal of the device of the invention is accomplished in the converse manner.

While I have shown and described one specific embodiment of the present invention, it will be seen that I do not wish to be limited exactly thereto, since various modifications may be made without departing from the scope of the invention, as defined by the following claim.

I claim:

An end protector for tubular articles comprising, in combination, a cap overlying the end of said tubular article and provided with an annular flange encompassing its exterior surface adjacent the end thereof, a flexible concavo-convex strip disposed within the tubular article with its ends extending into adjacency with respect thereto, said strip having its concave por-

tion facing said cap, a substantially U-shaped member disposed between said cap and said strip, the legs of said U-shaped member being extended toward said strip and having recesses in the extremities thereof to receive said strip at points adjacent the ends of the latter, the ends of said strip being of substantially constant width to permit the unrestrained movement thereof in the recesses in the extremities of the legs of said U-shaped member, a bolt extending through the approximate centers of said cap, said U-shaped member, and said strip, whereby the center portion of said strip may be influenced toward said U-shaped member to thereby press the extremities of said strip into contact with the tubular article, and a tubular spacer carried by said bolt and disposed between said strip and said U-shaped member.

HOWARD M. HICKS.
